COMBINED CIRCUIT MAKER AND BREAKER

Frank Marzo, Washington, D. C.

Application September 14, 1933, Serial No. 689,469

2 Claims. (Cl. 200—35)

This invention relates to an improvement in electric circuit makers and breakers and has particular reference to such a structure for use in connection with alarm clocks of the spring motor type.

It is an object of the present invention to provide switch devices so constructed and positioned as to be actuated upon the release and expansion of the alarm spring.

A further object is the provision of switch structures for the making and breaking of an electric circuit, such switch arranged to be actuated by the expansion of the alarm springs of the clock or clocks at predetermined settings of the said alarms, and it is contemplated to employ a single clock having duplicate alarm mechanisms, although individual clocks having but a single alarm each may be used.

The purpose of the present invention is the provision of an automatic circuit closer for use in connection with radios, lighting circuits, electric cooking vessels, annunciator systems and many other devices where it is desired to close a circuit at a predetermined time, and where it is desirable to interrupt said circuit after a predetermined period.

The invention contemplates a structure of extreme simplicity, employing clock mechanisms of conventional design, is relatively cheap to manufacture, is strong, durable and highly efficient in use.

Other important objects and advantages of the invention will be apparent during the course of the following description, reference being had to the accompanying drawings.

In the drawings:

Figure 1 is a front view of a clock structure embodying the invention.

Figure 2 is a rear view thereof.

Figure 3 is a vertical section through the clock casing showing the invention in elevation.

Figure 4 is a perspective view of one switch lever.

Figure 5 is a sectional view through a duplicate clock casing illustrating a modified use of the invention.

Figure 6 is an enlarged view of a switch structure and operating spring and

Figure 7 is a diagram of the circuit connections.

Referring specifically to the drawings, the numeral 10 indicates a casing having front and rear walls 11 and 12. The walls 11 and 12 are provided with the usual openings for receiving the clock dial and rear cover plate. As clearly

shown, a clock mechanism is indicated generally at 13 and embodies duplicate alarm mechanisms having duplicate springs 14 and 15, spring winds 16 and 17 and alarm sets 18 and 19. The structure so far described relates broadly to a single 60 clock mechanism constructed with duplicate alarm mechanism, each adapted to be individually set and released at predetermined intervals.

Circuit closing switches are indicated as a whole by the letters A and B, with switch A 65 serving as the initial circuit closer and switch B as the circuit breaker. Switch A comprises a substantially L-shape lever 20, pivoted at 21 to a wall of the casing 10. The long arm 22 of the lever overlies and is spaced from the spring 14 70 and carries a combined insulating and wear strip 23. The shorter arm carries an insulated contact 25, having connection with a wire 26. The contact 25 is adapted to engage a co-acting contact 27 carried by an insulated fixed bracket 28. A 75 wire 29 has electrical connection with this contact, and with a binding post 30 carried by an insulated block 31. A spring 32 normally urges the arm 22 downwardly for separating the contacts 25 and 27. Release of the alarm spring 14 80 will swing the arm 22 upward for bringing the contacts 25 and 27 into engagement.

Switch mechanism B embodies an L-shape arm 33, pivoted at 34, to a wall of the casing. The long arm 35 overlies and is in the path of 85 expansion of the spring 15, and carries an insulating and wear strip 36. The short arm 37 carries an insulated contact member 38 having electrical connection with a circuit wire 39, the wire 39 having its opposite ends connected with a binding post 40 carried upon the block 31. The contact 38 is adapted to normally engage a contact 41 carried by a fixed insulated bracket 42. The contact 41 is electrically connected with the wire 26. The arm 35 is normally urged downwardly by a spring 43 for maintaining the contacts 38 and 41 in engagement. A release of the alarm spring 15 will urge the arm 35 upward for separating the contacts 38 and 41. Circuit wires 44 and 45 lead 100 into the casing and have connection with the binding posts 30 and 40. The lead-in wires may be equipped with the conventional knife plug at their outer ends.

The operation of the structure so far described 105 is as follows:

Assume that the parts are in the position illustrated in Figure 3, with the alarm springs wound and set. In this position no current can 110 flow, since the switch A is in a disconnected po-

sition. It is of course intended that the alarm spring 14 be the first to operate, and when this occurs, the expansion of the spring 14 bearing against the arm 22, will raise such arm and 5 swing the arm 24 in its contact 25 into electrical contact with contact 27. Since contacts 38 and 41 are already in engagement, current will flow from wire 44 through wire 29, contacts 27 and 25, wire 26, contacts 41 and 38, wire 39, and back 10 to wire 45. At a predetermined time, the alarm spring 15 will be released and the expansion thereof will raise the arm 35 for swinging the arm 37 and its contact 38 out of engagement with the contact 41 for interrupting the circuit. 15 In order to reset the mechanism, it is only necessary to rewind the springs 14 and 15; the other parts automatically returning to their normal functioning position.

Referring now to the structure illustrated in 20 Figures 5 and 6, the numerals 46 and 47 indicate clock structures as a whole provided with conventional alarm springs 48 and 49. Switch structures designated C and D are arranged adjacent the clocks 46 and 47. Switch C embodies an L-shape lever 50, pivotally mounted at 51 upon a fixed bracket 52. The long arm 53 of the lever lies in the path of expansion of the spring 48, while the short arm 54 is provided with an insulated contact member 55 adapted 25 to engage an insulated contact member 56 carried by the bracket 52. The bracket 52 is suitably rigidly supported upon the clock frame as indicated. A spring 57 normally urges the arm 53 downwardly for separating the contacts 55 and 56.

Switch D embodies an L-shaped arm 58 pivotally supported at 59 upon a fixed bracket 60. The long arm 61 of the lever lies in the path of expansion of the spring 49, which the short arm 62 is provided with an insulated contact member 63 adapted to normally engage an insulated contact 64 carried by the bracket 60. A spring 65 urges the arm 61 downwardly for maintaining the contacts 63 and 64 in engagement. Contacts 55 and 63 are connected by a 40 wire 66. Contact 56 has connection with a wire 67, in turn connected with a binding post 68. Contact 64 has connection with a wire 69, in turn connected with a binding post 70. Lead-in wires 71 and 72 have connection with the binding posts 68 and 70.

The operation of this form of the invention is identical with that first described, with the exception that two clocks are employed instead of one.

It is to be understood that the invention is not limited to the precise construction set forth,

but that it includes within its purview whatever changes fairly come within either the terms or the spirit of the appended claims.

Having described my invention, what I claim as new is:

1. A structure of the character described comprising a casing, clock mechanism therein, said clock embodying two alarm mechanisms having independent alarm springs and sets, switch elements pivotally supported in said casing and comprising L-shape levers, one arm of each lever positioned over and in the path of expansion of one of said springs, insulating wear strips secured to the under faces of said arms for engagement with the alarm springs, contacts carried by the other arm of said levers, brackets supported in said casing and provided with contacts adapted to be engaged with the contacts of the arms, springs for urging the first named arms in a direction toward the alarm springs, one of said switches upon the expansion of its adjacent spring serving to close an electric circuit and the other of said switches serving to interrupt said circuit upon the expansion of its adjacent spring.

2. A structure of the character described comprising a casing, spring driven clock mechanism contained therein, said mechanism embodying two independent alarm mechanisms having independent alarm driven springs and sets, switch elements pivotally supported in the casing and comprising L-shape levers, one arm of each lever positioned over and in the path of expansion of its adjacent spring, leaf springs for said levers for moving the levers in a direction toward the alarm springs, contacts carried by the other arm of said levers, brackets rigidly supported in said casing in the path of movement of said last named arms, contacts carried by said last named arms and adapted to be engaged by contacts carried by the brackets, an insulating wear strip carried by each of the first named arms to be engaged by the said alarm springs, a conductor wire connected between the contact of one lever and the contact of a stationary bracket upon the opposite side of the casing, a pair of lead-in conductor wires for said casing, one of which has connection with the other of said levers and the other of which has connection with the other of said brackets, one of said switch elements upon the expansion of its adjacent spring serving to close an electric circuit, and the other of said switch elements upon the expansion of its adjacent spring serving to interrupt said circuit, substantially as shown and described.

FRANK MARZO.
